UNITED STATES PATENT OFFICE

2,634,848

COIN MAGAZINE FOR COIN-CONTROLLED LOCKS

Henry L. Beimel, Cambridge, Mass., assignor to
American Locker Company, Inc., Boston, Mass.,
a corporation of Delaware

Application November 8, 1950, Serial No. 194,709

3 Claims. (Cl. 194—92)

1

In my copending application Serial No. 122,116, filed October 18, 1949, now Pat. No. 2,603,335, July 15, 1952, I have disclosed a coin magazine attachment for coin controlled locks which converts a single coin lock into a lock requiring two or more coins to operate. The dime checking cabinet lock shown in Patent 1,640,605 requires the insertion of a single dime to operate the lock, and this lock is converted into a multiple coin lock when my said attachment is applied thereto.

The single dime checking cabinets have been in public use for many years and it occasionally happens that a patron drops a single dime into the two-dime lock and then, being unable to operate the lock, walks away and leaves the dime in the lock. The next patron drops a dime into the lock and then, knowing that the lock requires two dimes, tries to insert a second dime. This condition has caused wedging of the coins in the magazine with the second dime sliding beside the first dime and thereby jamming the lock and preventing its operation. The primary object of my invention herein is to provide means for eliminating this difficulty.

In the multiple coin magazine locks heretofore employed the foremost coin is positively engaged until released by the operation of the lock. In accordance with my present invention, means including a yielding body is provided on the coin magazine in position to engage the foremost coin and support the same and the coins rearwardly thereof in the magazine. The yielding pressure of the body on the foremost coin is sufficient normally to support the coins in the magazine, but not sufficient to prevent movement of the foremost coin from the magazine when pressure is applied thereto through the coins rearwardly thereof. Thus when a patron tries to deposit a third coin in the magazine he merely forces the foremost coin from the magazine and leaves two coins therein in position to operate the lock.

These and other features of the invention will be more readily understood and appreciated from the following detailed description of a preferred embodiment thereof selected for purposes of illustration and shown in the accompanying drawings in which:

Fig. 1 is a side elevation, partially broken away, of a coin controlled lock embodying my invention with two coins supported in lock operating position,

Fig. 2 is a fragmentary view of the opposite side of the lock,

Fig. 3 is a like view showing the foremost coin being forced from the magazine by the depositing of a third coin into the magazine, and

2

Fig. 4 is a front sectional view showing the lock in cabinet locking position.

The invention is particularly applicable to coin controlled locks of the nature shown in Patent 1,640,605 and, for purposes of description, I have herein disclosed my improved lock mechanism as applied to a parcel checking cabinet and requiring the insertion of two dimes to release the lock which is normally held in unlocked position.

In the drawing, 9 indicates generally a key cylinder equipped with the usual locking tumblers adapted to be manipulated by a key 11, which in the type of lock illustrated serves as an identifying check by which the customer may recover or obtain access to the belongings which he has deposited in a parcel locker.

The key cylinder is provided near its outer end with a locking bolt 12 adapted to be moved with the cylinder from the locked position of Fig. 4 to the unlocked position shown in broken lines. A fragment of the front plate of the locker cabinet frame is shown at 13 in Fig. 1. The front plate 14 of the lock is disposed over an opening in the plate 13, its lower end being provided with a lip 15 engaging the inner face of the plate 13 and its upper end being equipped with a lock (not shown) by which the plate 14 and the parts assembled thereon are detachably secured in position in the cabinet. A recorder 17 may be connected to the cylinder 9 so as to be operated by each actuation of the lock, whereby the number of lock actuations and consequently the number of coins deposited is recorded.

The front plate 14 is provided beneath the coin cylinder with a coin slot 18 through which coins can be inserted edgewise into the coin receiving magazine 19 at the back of the plate 14. The magazine illustrated is adapted to hold two coins 20 with the upper coin in position to be engaged by a feeler 22. The feeler is on the bottom end of a lever pivoted at 23 and having an arm 24 provided with a tooth 25 for engaging in a notch 27 of the lock cylinder. A spring 26 normally swings the lever in a direction engaging the tooth in the notch which thereupon serves to hold the lock in the unlocked position.

The bottom coin is held in the magazine between a leaf spring 28 and the laterally disposed end 29 of an arm 30 pivoted at 31, and the bottom coin supports the upper coin in position to be engaged by the feeler 22. The arm 30 is held in the coin supporting position by the free end 32 of a lever 33 extending over the free end of an arm 34 integral with the arm 30. The lever 33 is pivoted at 23 and has a projection 35 normally

extending into a recess 36 of the lock cylinder. A spring 37 normally rotates the lever 33 clockwise (Fig. 4) and keeps the end 32 disposed over the arm 34. When two coins are in the magazine and the lock is rotated clockwise (Fig. 4) the cam 38 engages the projection 35 and swings the lever 33 anti-clockwise, thus permitting the arm 30 to move upwardly and release the coins.

The improved feature of the invention herein disclosed resides in the spring 28 or like yielding body for engaging and supporting the bottom coin. Should a patron attempt to force a third coin 40 into the magazine the pressure thereof against the other coins will simply force the bottom coin past the spring 28, thereby preventing any jamming of the coins and leaving two coins in position in the magazine to operate and release the lock, it being understood that engagement of the feeler 22 with a coin in the magazine holds the tooth 25 away from the recess 27 and permits the lock cylinder to rotate from the unlocked position to the locked position shown in Fig. 4.

Having thus disclosed my invention what I claim as new and desire to secure by Letters 25 Patent is:

1. In a coin controlled lock movable to and from locking and releasing positions, means normally retaining the lock in one of said positions and coin feeler mechanism for rendering the retaining means inoperative when a coin is disposed in position to be engaged by the feeler; a magazine for receiving a plurality of coins in edge to edge relation with each coin rearwardly

of the foremost coin engaging the next adjacent coin therebeyond and with one of the rearward coins in position to be engaged by the feeler, the magazine including a yielding body disposed in position to engage the foremost coin and support the same and the coins rearwardly thereof in the magazine, the yielding pressure of said body on the foremost coin being adapted to permit passage of such coin from the magazine when pressure is applied thereto through the coins rearwardly thereof.

2. The coin magazine defined in claim 1 in which the yielding body comprises a leaf spring mounted on the magazine and having a free resilient portion disposed in position to engage with yielding pressure against the foremost coin in the magazine.

3. The coin magazine defined in claim 1 in which the yielding body comprises a leaf spring mounted on one marginal edge of the magazine and having a free resilient portion disposed in position to engage with yielding pressure against the adjacent edge of the foremost coin in the magazine.

HENRY L. BEIMEL.
